MACHINE GUARD

Frank Szypulinski, Milwaukee, Wis.

Application April 19, 1946, Serial No. 663,293

2 Claims. (Cl. 90—11)

1

My invention relates to guards, and more particularly to a type of guard that may be attached to a machine tool for the operator's safety.

The object of my invention is to provide a device of this type that will enable the operator to increase production because of his ability to guard himself against fast revolving cutters or the like while the work is being changed.

Another object of my invention is to provide a guard that will protect the operator against splashing of the lubricant directed onto the fast revolving cutter tool.

Still another object of my invention is to provide a device that will enable the operator to direct a steady flow of lubricant onto the cutter providing sufficient lubrication, yet not having to retard the flow while the cutter is brought to a stop during the operation of changing the work in the work holder.

Still another object of my invention is to so construct the support for the guard as to enable it to be adjustably positioned during the working operation as well as the changing operation without any mechanical change in the device.

Other and further objects of my invention will become more apparent as the description proceeds when taken in conjunction with the drawing, in which:

Figure 1 is a fragmentary side view of a machine tool showing a headstock and a slidably mounted tool support, the tool support having the guard assembly mounted thereon.

Figure 2 is a plan view of the guard assembly.

Figure 3 is a side view of the guard assembly as shown in Figure 2, and illustrating the adjustable feature shown in dotted lines.

Figure 4 is a perspective view of the device in a retracted position.

Similar characters of reference indicate corresponding parts throughout the several views, and referring now to the same, character 10 shows a guard member attached by means of rivets or bolts at 11 to a horizontal member 12, forming a part of the entire assembly with the member 12'. The member 12' is hingedly supported to a bracket 16 at 17 and the bracket 16 is attached to the tool support 19 by means of screws 18. There are sliding supports 13 and 13' encircling the arms 12 and 12', the support 13 being attached to the arm 12' at 14, and the sliding sup-

2

port 13' is attached to the arm 12 at 15. This permits extending the arms 12 and 12' outward, or retracting them, depending on the position of the guard 10, and when the cutter or tool, shown as 20 in Figure 1, engages the workpiece 23, held by the work holder 22 onto the headstock 21, the guard is raised, as shown in dotted lines in Figure 1. This will permit the guard to be out of the way while the tool is functioning, and to be disposed downwardly, as shown in Figure 1, covering the revolving tool 20, while the work is being replaced in the work holder 22. Obviously, it takes time to stop the cutter or tool from revolving, and the steady stream of lubricant that is directed to the cutter need not be retarded or lessened when the tool is retrieved away from the work.

The arm 12' rests on a support 24, forming an integral part of the bracket 16, when the guard is in a downward position.

It is manifest to anyone familiar with the art that machine tools are designed for speed in production and time is a very definite element and factor to be considered. When the tool is backed away from the workpiece, it is necessary for the operator to be protected against the revolving tool and the spray of the lubricant, while he removes the workpiece from the chuck and replaces it with another workpiece to be machined. Without the use of this type of guard, the operator would have to wait for the tool to come to the point where it no longer revolves before he could attempt removal of the work from the holder. But by the use of this type of guard, the guard will cover the revolving cutter without the operator waiting for it to stop.

While I have herein described a specific construction and shown its manner of use, I know that many changes and configurations of parts and elements may be made without departing from the operativeness of the invention and the scope of the appendent claims, and I herein reserve the right to make such changes as are deemed necessary without affecting the invention or the claims.

Having thus described my invention, what I claim and desire to secure by Letters Patent in the United States is:

1. A device of the character described comprising a hollow guard open at the bottom and rear

faces, an elongated arm secured to said hollow guard, a mounting bracket having an elongated arm hingedly connected thereto and arranged in parallel relation to the arm of said hollow guard, a support member connected to each of said arms for slideable adjustment of said guard with respect to said mounting bracket.

2. The structure of claim 1 wherein the mounting bracket has a stop member for engaging the arm hinged thereto for limiting downward movement of said guard. 10

FRANK SZYPULINSKI.
